US00D842713S

(12) **United States Design Patent** (10) Patent No.: **US D842,713 S**
(45) Date of Patent: **** Mar. 12, 2019**

(54) **THERMOSTAT**

(71) Applicant: **Honeywell International Inc.**, Morris Plains, NJ (US)
(72) Inventors: **Jonathan Erbacher**, Minneapolis, MN (US); **Travis Read**, Little Canada, MN (US); **Rajat Shail**, Stevensville, MI (US)

(73) Assignee: **Honeywell International Inc.**, Morris Plains, NJ (US)

(**) Term: **15 Years**

(21) Appl. No.: **29/610,157**

(22) Filed: **Jul. 10, 2017**

(51) LOC (11) Cl. **10-04**

(52) U.S. Cl.

USPC **D10/50**; D10/60

(58) **Field of Classification Search**

USPC D10/49, 50, 60; D13/162, 162.1, 164, D13/177

CLAIM

The ornamental design for a thermostat, as shown and described.

DESCRIPTION

FIG. 1 is a perspective view of a thermostat; FIG. 2 is a front elevation view of the thermostat of FIG. 1; and,

FIGS. 3-6 are left, right, top and bottom views, respectively, of the thermostat of FIG. 1.

The portions illustrated in broken lines on the figures depict unclaimed environmental subject matter and form no part of the claimed design.

1 Claim, 6 Drawing Sheets
